UNITED STATES PATENT OFFICE

HENRY I. WRIGLEY, OF CHICAGO, ILLINOIS, ASSIGNOR TO UNIVERSAL DRAFT GEAR ATTACHMENT CO., A CORPORATION OF ILLINOIS

HANDWHEEL FOR CAR BRAKES

Application filed December 18, 1929. Serial No. 414,852.

The invention relates to wheels employed in connection with the brake mechanism of railway cars for setting the brakes by hand. Its objects are to provide a wheel which may be conveniently grasped by the operator, will be safe in its operation, and which will prevent the objectionable but common practice of inserting a bar through the wheel, for engagement by the brake staff as a fulcrum whereby the effective leverage may be increased.

The above-named advantages are secured by the present invention which consists of a wheel, in disk form, of approximately uniform thickness, radially ribbed to increase its strength, and provided at its rim with a gripping flange, the wheel being without perforations of sufficient size or so disposed as to admit the use of a lever bar.

20 In the accompanying drawing illustrating the invention

Fig. 1 is a plan view of the wheel;

Fig. 2 is an edge view thereof viewed from the points indicated at 3—3 in Fig. 1 or from 25 points midway between such figures;

Fig. 3 is a diametrical section on the line 3—3 of Fig. 1; and

Figs. 4 and 5 are detail sections, respectively, on the lines 4—4 and 5—5 of Fig. 1.

30 The improved wheel is generally designated by the numeral 10 and preferably, and as shown, is a unitary casting. With the exception of its hub element 11 and its grip element 12, it is of approximately uniform thickness, thereby simplifying the molding operation and lessening the danger of casting imperfections, such as segregations. The hub 11 is socketed to receive the end of a brake staff, the socket being preferably tapered to 40 insure a tight fit.

The web of the wheel is sinuous circumferentially. The several convolutions, here shown as four in number, are sector shaped and are of the greatest depth, that is, in a direction parallel with the axis of the wheel, where they unite with the hub 11, as shown at 13, their depth gradually decreasing to the outer margin of the web, at 14, where they are nearly, but preferably not quite flat.

50 The web of the wheel is preferably some-

what dished, as plainly indicated in Figs. 3 and 4, and at its margin is continued as a flange 15 substantially parallel to the axis of the wheel, this flange preferably extending downwardly as shown, the dished face of the wheel being regarded as its top even though the wheel may be applied to a horizontal staff at the end or side of a car. At its outer or lower margin, the flange 15 curves outwardly and upwardly as shown at 16, and at its outer edge is preferably provided with a bead which constitutes the grip element 12. The margin of the web of the wheel, the flange 15 and the grip element 12 preferably follow an undulating line as shown, this form having as one of its advantages the provision of a more secure grip.

It is a common practice with operators to insert the hand or fingers through apertures in a brake wheel and to increase the leverage by inserting a bar through the wheel and engaging it with the brake staff. These practices frequently result in injury to persons or property by the accidental release of the brake; and the use of the lever is further objectionable because it often results in a too violent application of brakes causing the sliding of the car wheels on the rails to their serious injury.

These practices are effectually prevented by the wheel forming the subject of this application as it is devoid of openings, save mere drain holes, as 17.

I claim as my invention:

1. A disk wheel for brakes, the web thereof comprising a plurality of sector shaped convolutions of greatest axial dimension adjacent the center of the wheel.

2. A disk wheel for brakes, the web thereof being of substantially uniform thickness and comprising a plurality of sector shaped convolutions of greatest axial dimension adjacent the center of the wheel.

3. A disk wheel for brakes having a depending gripping flange at its margin, the disk and flange being of uniform thickness, the disk being circumferentially sinuous and comprising a plurality of sectors having a maximum depth adjacent the hub.

4. A hand brake wheel comprising a hub,

a substantially imperforate disk extending from the hub, its outer margin constituting the periphery of the wheel, and a flange extending transversely from such margin and of a depth constituting a grip member, the outer margin of the flange being in the form of a return bend.

5. A hand brake wheel comprising a hub, a disk extending from the hub, its outer margin

6. constituting the periphery of the wheel, and a flange extending transversely from such margin and of a depth constituting a grip member, the outer margin of the flange being curved outwardly.

15 6. A disk hand wheel for brakes having at its periphery a flange approximately normal to the plane of the wheel and of a depth to form a hand grip, the outer margin of the flange being curved outwardly and terminating short of the periphery of the disk.

7. In a disk hand brake wheel, a hub, and a web integral therewith, the web comprising a series of sector-shaped convolutions of maximum depth at the juncture of the web and

20 hub.

8. In a disk hand brake wheel, a hub, and a web integral therewith, the web comprising a series of sector-shaped convolutions of maximum depth at the juncture of the web and

30 hub, the periphery of the web being flanged downwardly, the margin of the flange being upturned.

9. As a new article of manufacture, a hand wheel for railway brakes comprising a unitary casting including a disc-shaped body having a central hub and a peripheral flange

35 of material depth disposed transversely to the plane of the body of the wheel to afford a hand grip, the body of the wheel between the hub and the flange being free from openings of a size that will permit the insertion of a bar or the hand or fingers of a brakeman.

10. As a new article of manufacture, a hand wheel for railway brakes comprising a unitary casting including a disc-shaped body having a central hub and a peripheral flange

45 of material depth disposed transversely to the plane of the body of the wheel, the outer periphery of the body and the flange being

50 configured to afford a hand grip, the body of the wheel between the hub and the flange being free from openings of a size that will permit the insertion of a bar or the hand or fingers of a brakeman.

75 In testimony whereof I affix my signature.
HENRY I. WRIGLEY.
